US00D963773S

(12) **United States Design Patent** (10) **Patent No.:** **US D963,773 S**
(45) **Date of Patent:** **** Sep. 13, 2022**

(54) **GOLF CLUB HEAD**(71) Applicant: **KARSTEN MANUFACTURING CORPORATION**, Phoenix, AZ (US)(72) Inventors: **Travis D. Milleman**, Portland, OR (US); **Xiaojian Chen**, Phoenix, AZ (US)(73) Assignee: **Karsten Manufacturing Coperation**, Phoenix, AZ (US)(**) Term: **15 Years**

D514,179 S	1/2006	Chen et al.

FIG. 1 is a top perspective view of a golf club head;
FIG. 2 is a bottom perspective view of the golf club head of FIG. 1;

FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1;
and,
FIG. 8 is a toe side view of the golf club head of FIG. 1.
The broken lines shown on the drawings form no part of the claimed design.
